VENETIAN BLIND

August F. Christiani, Red Lodge, Mont.

Application August 4, 1941, Serial No. 405,399

2 Claims.

(Cl. 20—62)

This invention relates to Venetian blinds, and its general object is to provide a blind that is primarily designed for use with hinged window sash, and to be carried thereby, as well as detachably secured thereto, in a manner whereby the blind can be readily applied and removed, so as to facilitate washing the sash, but casual removal or displacement is practically impossible. A further object is to provide a Venetian blind that includes a frame and a ladder tape for supporting the slats of the blind at their ends and intermediate their ends for adjustment of the slats to open and closed positions, and the slats can be readily removed for repairs or replacement.

Another object is to provide a Venetian blind that is simple in construction, inexpensive to manufacture, easy to install, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a front view of the blind which forms the subject matter of the present invention, with the slats in fully open position.

Figure 2 is an end view of the blind attached to a sash, and illustrates parts broken away and in section.

Figure 3 is a top plan view.

Figure 4 is a perspective view of one of the slats.

Figure 5 is a fragmentary detail perspective view illustrating the arrangement of the cross strips of the ladder tape and their relation with the slats.

Referring to the drawing in detail, it will be noted that my blind includes a frame which may be of any size and shape to fit sashes of various sizes and shapes, but in any event is made up of upper and lower bars 1 and side bars 2 joined together so that the rear faces of all of the bars are flush with each other to provide a flat rear surface to bear against the inner face of a window sash A of the hinged or swinging type, as indicated in Figure 2.

The blind is shown as being detachably secured to the sash, and for that purpose, the upper and lower bars 1 are each provided with a pair of slots 3 extending transversely thereof

for a portion of their width, from their outer longitudinal edges, as best shown in Figure 1. The slots are adapted to receive the shanks of right angle screw hooks 4 that are threaded in the sash, and by that construction, it will be obvious that the blind is not only carried by the sash, but can be readily applied and removed with respect thereto, the blind being held in place against casual removal or displacement when the heads 5 of the hooks are directed toward each other, or in other words in latched position, and bearing against the front face of the bars 1, and when it is desired to remove the blind, the hooks are turned for disposal of the heads away from each other or in a released position to allow passage of the heads through the slots.

The side bars which preferably have their upper and lower ends rounded, as best shown in Figure 2, are of a width to extend a consider-

able distance forwardly of the upper and lower bars, and the side bars are each provided with a row of equi-distantly arranged circular openings 6 along the length thereof to provide bearings for the trunnions 7 of slats 8. The slats are of course flat and relatively thin and are made from any flexible material suitable for the purpose. The trunnions which are also flat are provided merely by cutting away the corner portions of the slats in right angle formation, in a manner so that the trunnions extend centrally from the ends of the slats, as best shown in Figure 4. While the trunnions are rotatably mounted in the bearing openings 6, they are of a width to set up a slight frictional engagement with the walls of the openings, so that the slats will remain in any position in which they are adjusted.

The slats are connected together for adjustment in unison, when any one of the slats is moved, and for that purpose I provide a ladder tape or web that includes a relatively wide continuous single strip 9 of any suitable material, that is looped about the upper and lower slats for disposal transversely thereof to provide parallel vertical portions 10 arranged midway the ends of all of the slats, as best shown in Figure 1. Secured to and bridging the parallel portions 10 is a plurality of relatively narrow cross strips 11, there being a single cross strip 11 for each of the upper and lower slats for cooperation with the transverse portions of the strip 9 to engage the flat faces of the upper and lower slats, while a pair of cross strips 11 are provided for each of the other slats for engagement with the flat faces thereof, and the strips 11 are alternately arranged

relative to each other, that is every other strip 11 is flush with one side edge of the parallel portions 10 and the remaining strips 11 are flush with the opposite side edges thereof, as best shown in Figure 1. The fastened end portions of companion cross strips are preferably arranged in opposite directions, as best shown in Figure 2, that is the end portions of one companion cross strip are directed downwardly while the end portions of the other companion strip are directed upwardly, so as to allow free insertion of the slats between the companion strips, as will be apparent, when it is desired to replace broken or otherwise damaged slats. The fastened end portions of the strips 11 for the upper and lower slats are likewise arranged to facilitate easy insertion of slats between those strips and the transverse portions of the strip 9.

It is thought from the foregoing description that the advantages and novel features of the invention will be readily apparent.

It is to be understood that changes may be made in the construction and in the combination and arrangement of the several parts; provided that such changes fall within the scope of the appended claims.

What I claim is:

1. The combination in a Venetian blind structure, of a frame assembly comprising top, bottom, and side bars joined together at their ends to lie against and be attached to a window sash, the side bars each having horizontally aligned, uniformly spaced circular openings of substantially the same diameters, a plurality of slats each hav-

ing flat end trunnions fitting in aligned pairs of the openings in the side bars and of a width giving frictional resistance against casual pivotal movement in said openings thereby to pivotally support said slats in the frame and hold the same in predetermined positions in said frame unless positively moved, and means comprising a ladder tape for moving all of said slats in unison, said tape formed to permit removal of any one or all of said slats from the frame.

2. The combination in a Venetian blind structure of a frame assembly having top, bottom and side bars joined together at their ends to lie against and be attached to a window sash, the side bars each having horizontally aligned, uniformly spaced circular openings of substantially the same diameters, a plurality of flat, flexible slats cut away at their ends to provide flat trunnions fitting in aligned pairs of the openings in the side bars, said trunnions being of a width giving frictional resistance against casual pivotal movement in said openings thereby to pivotally support said slats in the frame without rattling and hold the same in predetermined positions unless positively moved, and a ladder tape for moving said slats in unison having parallel vertical parts arranged in front and in back of the slats respectively, and cross pieces above and below each slat of less width than the width of the vertical parts and relatively staggered and having end tabs for connection with the vertical parallel parts, said tabs being directed away from the adjacent slats to facilitate withdrawal of slats.

AUGUST F. CHRISTIANI.
